DESIGN FOR A THERMOMETER

Walter Dorwin Teague, Forest Hills, N. Y., assignor to Taylor Instrument Companies, Rochester, N. Y., a corporation of New York

Application July 26, 1933. Serial No. 48,835

Term of patent 3½ years

To all whom it may concern:

Be it known that I, WALTER DORWIN TEAGUE, a citizen of the United States of America, residing at Forest Hills, county of Queens, State of New York, have invented a new, original, and ornamental Design for a Thermometer of which the following is a specification; reference being had to the accompanying drawing, wherein:

Fig. 1 is a front elevation;

Fig. 2 is a side elevation; and
Fig. 3 is a cross-sectional view taken substantially on the line 3—3 of Fig. 1, of the thermometer showing my new design.

I claim:

The ornamental design for a thermometer, as shown.

WALTER DORWIN TEAGUE.
